[57] CLAIM

The ornamental design for a combined front panel display and associated input unit for a video camera, as shown and described.

DESCRIPTION

FIG. 1 is a perspective view of a combined front panel display and associated input unit for a video camera; FIG. 2 is an enlarged front elevational view thereof; FIG. 3 is a perspective view of a second embodiment of the combined front panel display and associated input unit for a video camera; and,

FIG. 4 is an enlarged front elevational view thereof. The broken line showing of a video camera is for illustrative purposes only and forms no part of the claimed design.
